CLAIM

The ornamental design for a combined coin holder and vanity mirror for an automobile dash, as shown and described.

DESCRIPTION

FIG. 1 is a right front perspective view of a combined coin holder and vanity mirror for an automobile dash in a closed condition showing my new design;

FIG. 2 is a right front perspective view of the combined coin holder and vanity mirror for an automobile dash in open condition;

FIG. 3 is a top plan view of the combined coin holder and vanity mirror for an automobile dash as taken from FIG. 1;

FIG. 4 is a front elevational view;

FIG. 5 is a right side elevational view, the left side being a mirror image thereof; and

FIG. 6 is a bottom plan view thereof.

FIG. 1

FIG. 2

FIG. 3

FIG. 4

FIG. 5

FIG. 6
